JOSEPH LAPONE, OF NEW YORK, N. Y.

STRIKING MECHANISM FOR CLOCKS.

1,264,817.

Specification of Letters Patent. Patented Apr. 30, 1918.

Application filed April 18, 1917. Serial No. 162,872.

To all whom it may concern:

Be it known that I, JOSEPH LAPONE, a citizen of the United States, residing at New York, in the county of New York and 5 State of New York, have invented new and useful Improvements in Striking Mechanism for Clocks, of which the following is a specification.

This invention relates to time clocks, having mechanism designed to sound the hours and other determined periods of time, and the main object of the same is to combine with the striking or sounding mechanism means whereby the different divisions of 15 time will be understood by different sound strokes.

Another object of the invention is the provision in a clock of mechanism capable of producing such differences in sound and 20 such differences in strokes that the hearer will be able to determine exactly by the sounds and strokes the particular divisions of time.

With these and other objects in view, 25 the invention resides in the details of construction, and in the combination and arrangement of parts hereinafter described and shown in the accompanying drawings, forming a part of this specification, and 30 in which:—

Figure 1 is a view in front elevation of a fragmentary portion of the time clock, illustrating an embodiment of my improved 35 striking mechanism.

Fig. 2 is a diagram in front elevation, illustrating how my improved mechanism is connected with associated and coöperating parts, the mechanism being shown as it 40 appears when about to sound a division of time.

Fig. 3 is a view similar to that of Fig. 2, but illustrating the mechanism as it appears when sounding a division of time.

Fig. 4 is a view in side elevation of a 45 fragmentary portion of a time clock embodying my mechanism, certain parts being shown broken away in order more clearly to illustrate other parts.

Fig. 5 is a detail view of the peripherally notched wheel for measuring off the 50 periods of time for the proper execution of the sound strokes, a portion of the notch engaging lever also being shown.

With more particular reference to the accompanying drawings the numeral 10 denotes the metallic skeleton frame which is

employed to support the operating mechanism in the usual way, the said frame being rigidly supported by brackets as 11, attached to supports as 12, carried by the 60 clock frame 13. This skeleton frame 10 may be of any ordinary construction and may be supported in the clock frame 13 in any manner common to the art. As the general operating mechanism herein illustrated is similar to that of ordinary clock constructions having a pendulum, and having means for sounding divisions of time, it is deemed necessary to make only such brief description thereof as will enable those 70 familiar with the art to comprehend how my improvement for differentiating between the different divisions of time are connected with and operated by the well-known mechanisms. 75

The type of clock herein considered has two trains or systems of wheels—one for operating the pendulum, and, resultantly, the hands; and the other for operating the striking mechanism. Each train or system 80 is operated by its own main spring, and accordingly will be traced separately. As my improvements relate in part to each system, they will be so described in part in connection with the tracing of each system. Afterward their coöperative action will be described. 85

As best shown in Fig. 1 the train of wheels for the operation of the pendulum and also of the hands consist of a spring motor driven wheel 14, a pinion 15, a wheel 16 fast therewith, a pinion 17 in mesh with the wheel 16, a wheel 18 fast with the pinion 17, a pinion 19 in mesh with the wheel 18, a wheel 20 fast with the pinion 19, a pinion 21 in mesh with the wheel 20, a scape-wheel 22 fast with the pinion 21, said scape-wheel 22 representing the one upon which the escapement 23 operates for the reciprocation of the pendulum 23' in the 100 usual way. The wheel 16 also meshes with the pinion 24 which is fast on the minute hand shaft 25 for the rotation of the clock hands (not shown). All of said wheels are fast upon suitable shafts, rotatably secured 105 in the skeleton frame 10 in the customary manner.

Fast upon the minute shaft 25 in front of the frame 10 is a pinion 26 in mesh with a wheel 27, which carries on its outer face 110 near its toothed periphery three projecting pins as 28, the purpose of which will be

later described. Revoluble upon the minute shaft 25, in front of the pinion 26, is a sleeve 29 carrying on its inner end a wheel 29' which meshes with a pinion 30 fast with 5 the pin wheel 27 and rotatable therewith upon the stud 31. Thus, with the train in operation, the sleeve 29, which operates the hour hand, is driven by the minute shaft 25 through pinion 26, pin wheel 27, 10 pinion 30, and wheel 29'. The shaft 25, and accordingly, pinion 26, is driven at the rate of one revolution per hour; the pin wheel 27 is geared so as to make one revolution every three hours; and the wheel 29' is 15 geared so as to turn the sleeve 29 once in every twelve hours.

Turnable upon the skeleton frame 10 below the pin wheel 27 is a disk wheel 32 having eccentrically secured upon its face the 20 angular rod 33, the lower end of which is provided with a weight or hammer 34, the purpose of which is to strike the bell 35 when a division of time is to be sounded, as will be later described. Secured to the 25 rod 33 above the wheel 32 is an angular rod 36 which extends upwardly in an inclined direction and which is prolonged at its top end into an inwardly and downwardly projecting portion 37, lying normally 30 beyond the corner end of the skeleton frame 10, as best shown in Figs. 1 and 3.

As the wheel 27 revolves, the pins impinge successively upon the upper end of the rod 33, which end lies normally in the 35 path of said pins. Each time a pin impinges upon the rod, the disk 32 is turned on its axis raising the hammer 34 above the bell 35. When the hammer 34 has thus been raised, the pin under the revolution of the 40 pin wheel 27, passes over the end of the rod 33, so that the hammer 34 urged by a pull spring 38 fast with rod 36, drops down quickly, striking a blow upon bell 35, and sounding the same. This action occurs each 45 time a pin as 28 impinges the rod 33, or in other words, under the present construction, it occurs at a predetermined time on every hour, since the pins are equi-distant from each other, and since the pin wheel makes 50 one complete revolution every three hours. Conjunctionively with each raising of the hammer rod 33, the inclined rod 36, fast therewith, is pulled inwardly as shown in Fig. 2, so that the projecting end 37 is drawn over 55 the corner of the skeleton frame 10; and immediately the hammer 34 strikes to sound the bell 35, the said end 37 is again drawn beyond the corner of the skeleton frame 10 to its normal position. Thus, I arrange for 60 the sounding of the bell 35 at predetermined periods through the operation of the wheel 27, and for the simultaneous operation of the lever 36 for a purpose to be later described.

65 The train of wheels for operating the

usual striking mechanism for indicating the hour and half-hour divisions of time will now be described. This clock-train or system is like that usually employed for this purpose, and no improvements are 70 claimed therein, except in connection with the governing wheel for controlling the number of sound strokes.

As best shown in Fig. 4, the wheel 40, fast upon the shaft 41, is driven by the main 75 spring 42, the ratchet wheel 43 and co-operating dog 44 acting against the tension of the main spring 42 to hold it in operative position in the usual manner. The said drive wheel 40 meshes with the pinion 41' fast 80 with the wheel 42' upon the shaft 43' revolubly secured in the skeleton frame.

The wheel 42' meshes with the pinion 44' fast upon the shaft 45, also revolubly mounted in the skeleton frame. Fast with the 85 pinion 44' is a wheel 46 which is equipped near its toothed periphery with six outwardly projecting pins as 47, each equi-distantly spaced from the other. This wheel 46 meshes with the pinion 48 fast upon the 90 revoluble shaft 49, which on its opposite end carries a disk 50 having a notch 51 cut in its periphery. Also fast upon this shaft and with last said pinion is a wheel 55 in mesh with a pinion 56 fast on the revoluble 95 shaft 57, which fixedly carries a fan element 58.

Fast upon the shaft 43' at the rear side of the skeleton frame 10 is a wheel 59 which meshes with a wheel 60 rotatable upon a 100 stud shaft 61. Fixedly secured to the hub of the wheel 60 and rotatable therewith upon stud 61 is the governing wheel 62, which controls, by means of its peripheral system of notches, the sounding of the 105 strokes for the hour and half-hour divisions of time.

This governing wheel 62 is arranged in such manner as to make one exact revolution in each period of twelve hours, and it is provided on its periphery with a system of notches 63 which are spaced apart at successively increasing distances by two, in such manner as to form sections or lands on the periphery, each successive two of 110 which are relatively longer in length than their predecessors. Obviously, the purpose of this is to compensate for the increasing series of numbers from one to twelve, both on the hour and on the half-hour; but it is 115 important to note here that since both at one o'clock and at half-past one, this striking mechanism is required to operate only once, no sections or lands appear for these corresponding positions. Instead the whole 120 space, without lands, is represented by *a* and *b*. Following this space, the letters *c* and *d* represent the sectors or lands of that length necessary to enable the clock to strike two o'clock and half-past two, respectively; 130

the lands *e* and *f* are longer to enable the clock to strike three and half-past three, respectively; and the lands *g* and *h* are still longer to enable it to strike four and half-past four, respectively. Thus, the lands increase successively by twos around the periphery of the wheel 62, as indicated in Fig. 5, until the lands *w* and *x* compensate for the time necessary to enable the clock to 5 strike twelve and half-past twelve, respectively.

We now come to the means carried by the clock, and adapted to engage the notches as 63 for striking off the hours and half-hours. Fast upon the minute shaft 25 near the rear end thereof and upon oppositely disposed sides thereof are the angular contact pins 65. Revolubly secured in the skeleton frame below the minute shaft 25 is a 10 rock-shaft 66, to which is rigidly secured the following pins:—a pin 67, which extends outwardly through a suitable opening in the skeleton frame, and which is prolonged into an outwardly projecting end of 15 a suitable size and form for engagement with the notches as 63 of the governing wheel 62; a pin 68 which projects upwardly and engages with the end of a bell crank lever to be later described; and a pin 69 which projects upwardly and is provided with an angular end suitable for engaging the notch 51 in the disk wheel 50. The said pins 67 and 69 are so projected from the rock-shaft that they are adapted respectively to engage 20 25 30 35 40 45 50 55 60 65 70 75 80 85 90 95 100 105 110 115 120 125 130

wheels or clock-train is to cause a hammer 76 to strike a blow or blows upon a bell (not shown) having a sound or tone different from that of bell 35. The hammer 76 is carried on the end of the hammer rod 77, the 70 opposite end of which is fixedly secured to the end of a rock-shaft 78, rotatably mounted in the end of the skeleton frame in front of the pin wheel 46. Fixedly secured to this rock-shaft 78, and projecting inwardly past 75 the periphery of the pin wheel 46 so as to engage successively the pins 47 thereof, is a tilting rod 79. As the pin wheel 46 revolves away from the rock-shaft 78, as best shown in Figs. 2 and 3, the rod 79, resting upon a pin as 47, is carried upward by the rotation of the pin wheel so as to turn the rock-shaft 78 and raise the hammer 76. When the pin wheel 46 has revolved far enough, the rod 79 slides off the rear of a pin as 85 47, and, under the weight of the hammer 76 or a suitable pull spring, is drawn down upon the next succeeding pin for the next operation. Every time the pins 79 thus slides off a pin as 47, the hammer 76 drops 90 and strikes a blow upon its bell.

In the operation of the construction herein considered, one of the angular contacts 65, carried by the minute shaft 25, impinges upon the spring plate 73 of the bell crank 95 lever 70, on the hour while the other contact 65 similarly impinges said plate on the half-hour. With each impingement the pin 67 is removed from a notch as 63 simultaneously with the disengagement of the lever 100 105 110 115 120 125 130 135 140 145 150 155 160 165 170 175 180 185 190 195 200 projecting end 37 in engagement with the fan element 58, as best shown in Fig. 2; so that, even though the pins 67 and 69 have been disengaged from their respective notches, that striking mechanism will be held locked, by the locking of the fan 58, until the hammer 34 falls to strike a blow upon its bell 35. Thus, on each half-hour, the hammer 34 strikes a blow upon the bell 35 10 a moment or so before the regular striking mechanism is actuated.

While in the foregoing description and in the accompanying drawings, I have shown a mechanism for differentiating, by sounds 15 and by strokes, between the half-hours and the hours, it will be obvious that the same method may be employed with the introduction of the proper parts and with the proper changes in the gearing ratios, for similarly 20 indicating and differentiating between the quarter-hour and the three-quarter-hour divisions of time.

Having thus described my invention, what I claim is:—

25 In a striking attachment for clocks, the combination with a trip wheel and a fan

wheel supported for rotation upon parallel axes, the latter being supported in a plane higher than and to one side of the former, and independent means for driving them; 30 a disk pivoted for rocking movement below said trip wheel, a striking arm secured eccentrically to said disk, the lower portion of said arm below said disk being bent at an angle, an angular locking arm rigidly connected with said striking arm above said disk and extending in the path of said fan wheel, resilient means combined with said locking arm to normally maintain the same out of engagement with said fan wheel with 35 the striking arm in the path of said trip wheel whereby, when the striking arm is tripped, the locking arm will be drawn into the path of said fan wheel locking the same against movement, and means combined with 40 the lower end of said striking arm for delivering a blow under the tension of said resilient means after each tripping action.

45 In testimony whereof I have signed my name to this specification.

JOSEPH LAPONE.
